UNITED STATES PATENT OFFICE.

JOSIAH BLACK, OF LANSING, MICHIGAN; SPENCER D. KELLY ADMINISTRATOR OF
SAID JOSIAH BLACK, DECEASED.

GASOLENE-DISPENSING DEVICE.

1,344,478.

Specification of Letters Patent. Patented June 22, 1920.

Application filed January 23, 1918. Serial No. 213,400.

To all whom it may concern:

Be it known that I, JOSIAH BLACK, a citizen of the United States, residing at Lansing, in the county of Ingham and State 5 of Michigan, have invented new and useful Improvements in Gasolene-Dispensing Devices, of which the following is a specification.

The present invention relates to an apparatus adapted for pumping and measuring combustible liquids, preferably gasolene.

The primary object of the present invention is the provision of an apparatus of the above stated character primarily adapted 15 for installation at supply stations and one wherein the parts thereof can not be damaged by the flow of the gasolene therethrough and consequently presenting a strong, efficient and durable apparatus.

20 A still further object of the invention contemplates among other features, the provision of means for supporting the secondary tank to the pump in order that the latter may be swung at various angles for 25 convenience in discharging the gasolene into the tanks of motor driven apparatus.

With the above and other objects in view, the invention consists in the novel features, details of construction and combination of 30 parts which will hereinafter be more fully set forth, illustrated in the accompanying drawings and pointed out in the appended claims.

In the drawings:

35 Figure 1 is a general view of the complete apparatus in elevation;

Fig. 2 is a side elevation showing the secondary tank and its housing or tubing in vertical section; and

40 Fig. 3 is a view similar to Fig. 1 showing the tank in a swung position and its supply pipe in an extended position.

Fig. 4 is a section taken on line 4—4 of Fig. 2.

45 Fig. 5 is a detail vertical section illustrating a slightly modified form of dispensing means for the discharge pipe.

Referring more particularly to the accompanying drawings, in which like characters of reference refer to corresponding parts in the several views, the apparatus is 50 generally denoted by the character 5 and illustrating the reservoir 6 embedded in the ground and with which is connected the pump 7. Connected with the upper end of

the pump 7 is a supply pipe 8 terminating at its upper end in an L-shaped branch portion 9, the vertical portion 10 of which depends from the horizontal portion 9 in spaced parallelism with the supply pipe 8. 60 Mounted for vertical adjustment on the vertical portion 10 of the supply pipe is a sleeve 11 provided on its periphery with a plurality of diametrically opposite hooks 12 through which is connected the sling 13, 65 here shown for the purpose of illustration as constituting a flexible chain. Connected with the vertical branch portion 10 of the supply pipe at a point below the sleeve 11 is a hood 14 of substantially semi-spherical 70 formation and in which is universally mounted an enlargement 15 of substantially spherical formation and provided with an open upper end 16 for convenience in cleaning, repairing or gaining access to the interior thereof. The closed bottom of the enlargement is centrally provided at a point below and in vertical alinement with the discharge end of the vertical branch portion 10 with an outlet opening 17 in which 75 is supported a strainer 18. Obviously, when the sling 13 is attached to the sleeve 11, by the connection of the same with its hooks 12, this sling embraces both the hood and auxiliary tank and serves to adjustably and 80 rotatably support the tank on the branch portion 10 and for movements in various directions, to facilitate the swinging of the discharge pipe 19 when supplying the gasolene to the tanks of motor driven vehicles, (not 85 shown). The sling 13 further facilitates supporting the tank snugly within the hood, to prevent the entrance of rain water or the like within the tank and to further establish a universal connection between the 90 tank and hood. Attached to the bottom of the enlargement 15 at a point in embracing relation with its outlet 17, and depending therefrom, is a tubular casing 20 through 95 which the discharge pipe 19 passes, and this casing consists of an upper section 21 and a lower section 22 united together at the point 23 for either a fixed connection with one another or a telescopic mount, as desired. The lower end of the lowermost section 22 of this casing is funnel-shaped as at 24, to accommodate the nozzle 25 to slide upwardly and within the same and be supported therein through the provision of a loop 26 suspended from an eye 27 secured 100

105

110

inwardly and to the funnel-shaped end 24 of said casing. These loops or hooks 26 are adapted to retain the telescopic upper and lower sections denoted respectively by 5 the characters 28 and 29 against sliding movement, or in other words, hold the supply pipe in folded position when the use of the same is not desired. To obviate the wear of the confronting faces of these sections 28 and 29 upon the adjustment of the supply pipe, an inturned flange 30 is provided at the upper end of the lower section 29 and a second inturned flange is provided at the lower end of the uppermost section 15 28, and designated by the character 31, thereby reducing the friction between the pipes. The supply of the gasoline from the pump 7 into the enlargement 15 is controlled through the medium of a valve 32 20 installed within the supply pipe 8.

In the modified construction illustrated in Fig. 5 of the drawing I have illustrated the hood 14 as provided with a filling opening 37 closed through the medium of a cap 25 38. Clips 35 and 36 are provided for the connection thereto of a flexible chain 34. The clip 35 is provided on the extreme outer end of the supply pipe 8 while the clip 36 is disposed inwardly and secured to the enlargement 15.

From the foregoing description, taken in connection with the accompanying drawings, the advantages of construction and the method of operation will be readily ap-

parent to those skilled in the art to which 35 the invention relates, and while I have described the principles of operation of the invention, together with the device which I now consider to be the best embodiment thereof, I desire to have it understood that 40 the device shown is merely illustrative and that such changes may be made when desired as are within the scope of the appended claims.

Having thus described the invention, what 45 is claimed as new, is:—

1. In an apparatus of the character set forth, in combination, a supply pipe having an enlargement provided with a tubular casing projecting therefrom and having a 50 funnel-shaped end, an adjustable discharge pipe connected with and communicating with said enlargement and passing through said casing, and means in the casing for engagement with the discharge pipe for holding the latter in retracted position.

2. The combination with a pump and a supply pipe leading therefrom, of an enlargement into which one end of the supply pipe discharges, a non-flexible telescopic discharge pipe carried by said enlargement, a casing inclosing said discharge pipe, and means suspended in said casing with which one end of the discharge pipe engages for holding the latter against movement. 65

In testimony whereof I affix my signature.

JOSIAH BLACK, M. D.
